DESIGN FOR A STEREOSCOPE

Charles D. Austin, Cincinnati, Ohio, assignor to
Advertising Displays Inc., Covington, Ky., a
corporation of Kentucky

Application March 8, 1940, Serial No. 90,777

Term of patent 7 years

To all whom it may concern:

Be it known that I, Charles D. Austin, a citizen
of the United States, residing at Cincinnati, in
the county of Hamilton and State of Ohio, have
invented a new, original, and ornamental Design
for a Stereoscope, of which the following is a
specification, reference being had to the accom-
panying drawing, forming a part thereof.

Figure 1 is a front elevational view of a stereo-
scope showing my new design.

Figure 2 is a top plan view.

Figure 3 is a front perspective view.

Figure 4 is an elevational view of the back of
the stereoscope.

Figure 5 is an elevational view of the side of
the stereoscope.

I claim:

The ornamental design for a stereoscope, sub-
stantially as shown.

CHARLES D. AUSTIN.
